UNITED STATES PATENT OFFICE

2,565,305

AUTOMATIC TURRET LATHE

Louis E. Godfriaux, Madison, Wis., assignor to
 Gisholt Machine Company, Madison, Wis., a
 corporation of Wisconsin

Application June 2, 1945, Serial No. 597,268

33 Claims. (Cl. 29—42)

1

This invention relates to an automatic turret lathe, and more particularly to the control of the speed of the various parts during feed, and the automatic shifting of traverse and feed movements through successive cycles of operation of the lathe.

The principal object of the invention is to simplify and improve the construction of automatic turret lathes to thereby substantially reduce the cost of the same and the maintenance thereof, and provide a greater range of utility for such lathes.

Another object of the invention is to provide a turret lathe in which a greater range of speeds and feeds is provided for the several parts including the turret and the tool post, and in which the parts may be fed at any rate within the range of speeds provided therefor.

A more specific object is to provide a hydraulic control of the turret and tool post feeds giving a wide range of speeds with infinite selections within the range.

Another object is to provide a high power pump and motor unit for feeding a part of the lathe under infinite selections as to speed.

Another object is to provide a cam drum on the bed of the lathe indexed with the turret and which controls the feeds for each cycle of operation, determines the spindle speed and initiates and terminates the various feed and traverse movements.

Other objects will appear hereinafter in the description of a preferred embodiment of the invention, illustrated in the accompanying drawings.

In the drawings:

Figure 1 is a side elevation of a lathe embodying the invention;

Fig. 2 is an end view looking at the headstock and drive;

Fig. 3 is a schematic horizontal section through the headstock showing the hydraulic clutch control and gear shift mechanism;

Fig. 4 is a detail section taken on line 4—4 of Fig. 3 showing the high and low gear clutch actuating mechanism;

Fig. 5 is a section through the headstock control valve showing schematically the control connections;

Fig. 6 is a side elevation showing the hydraulic connections between the headstock and the turret carriage;

Fig. 7 is a longitudinal section of a telescopic connection for the hydraulic feed pipes shown in Fig. 6;

2

Fig. 8 is a longitudinal vertical section through the pump and motor unit on the turret carriage;

Fig. 9 is a transverse section through the pump taken on line 9—9 of Fig. 8;

Fig. 10 is a transverse section through the motor taken on line 10—10 of Fig. 9;

Fig. 11 is a longitudinal section through the traverse forward and reverse clutch;

Fig. 12 is a transverse section through the feed and traverse clutch taken on line 12—12 of Fig. 11 and showing the cam drum control;

Fig. 13 is an enlarged perspective view of a portion of the cam drum showing the shape of the cams and their attachment;

Fig. 14 is a detail transverse section looking at the forward end of the turret carriage and showing the cam drum;

Fig. 15 is a front elevation of the turret carriage with parts sectioned to show the control mechanism;

Fig. 16 is a transverse section taken on line 16—16 of Fig. 1 and showing the tool post carriage and cross slide;

Fig. 17 is a rear end view of the lathe with the cover plate removed and showing the indexing mechanism for the drum and turret;

Fig. 18 is a detail horizontal section of the drum indexing mechanism taken on line 18—18 of Fig. 17;

Fig. 19 is a detail section showing the drum index lock; and

Fig. 20 is a schematic hydraulic control circuit layout for the lathe.

The lathe comprises, in general, a bed 1 with an oil drip pan 2 preferably above the floor level, a headstock 3, a tool post 4 and a turret 5, which may be of regular standard construction for non-automatic lathes.

The headstock

40 The headstock is driven by a motor 6 through belt 7 and drive shaft 8. Clutch 9 is adapted to provide two different forward speeds by alternatively connecting the spur gears 10 and 11 on drive shaft 8 through the clutch to drive the intermediate shaft 12.

The high speed drive for spindle 13 is provided by clutch 14 on shaft 12 which drives the triple gear member 15 at the rotary speed of the shaft.

45 A triple gear 16 is splined to the auxiliary drive shaft 17 and may be shifted longitudinally to either of three positions relative to member 15 to effect three different speeds. Lever 18 on top of the headstock effects shifting of gear 16.

50 A double gear 19 splined on shaft 17 meshes

alternatively with gear 20 or with gear 21 on the spindle 13 to drive the latter. The shifting of gear 19 to its alternative positions is effected by lever 22 on top of the headstock.

The low speed drive for spindle 13 is provided by small gear 23 on shaft 12 driving the large clutch housing gear 24 floating on the low-speed gear shaft 25. A clutch 26 effects driving of shaft 25 by the rotation of gear 24. A gear 27 on shaft 25 meshes with a drive gear 28 on triple-gear member 15.

Alternate operation of clutches 14 and 26 effects either high or low speed driving of spindle 13.

Clutches 9, 14 and 26 are operated by hydraulic cylinders in response to a master control valve 29, shown in Fig. 5.

The cylinder 30 for clutch 9 is disposed at the forward end of shaft 12 and has a piston 31 with a piston rod 32 extending axially of the shaft to engage the clutch operating lever 33.

The cylinder 34 for operating clutches 14 and 26 is disposed conveniently on the top of the headstock and has a piston 35 with a piston rod 36 having a roller 37 at its end riding in a curved recess 38 at the end of a lever 39 fixed to the vertical shaft 40. A lever 41 on the lower end of shaft 40 effects simultaneous operation of yokes 42 and 43 which in turn operate the corresponding clutches 14 and 26.

When lever 39 is pushed outwardly by piston roller 37 the yoke 43 is moved to tighten clutch 26 and yoke 42 is moved to loosen clutch 14. When lever 39 is pulled inwardly by piston roller 37 the yoke 43 is moved to loosen clutch 26 and yoke 42 is moved to tighten clutch 14.

Control valve 29 comprises a vertically disposed valve chamber having a plunger valve body 44 therein with suitable ports and passages to control the operation of the pistons 31 and 35.

The plunger 44 is moved up and down to its several positions by the rack 45 and gear 46 meshing therewith. A spring 47 forces the plunger 44 upwardly against the top of the valve cylinder and gear 46 operates against the spring to move plunger 44 downwardly to its several operative positions.

The hydraulic connections through the valve are from pump 48 to intake port 49, through the valve and respective cylinders and returning by discharge port 50 and conduit to sump 51.

As shown in Fig. 5 the pressure fluid entering the valve through port 49 passes upwardly around the plunger 44 to port 52 from where it is conducted to the right-hand end of cylinder 34. Fluid is exhausted from the left-hand end of cylinder 34 to port 53 in valve 29 and from thence through passage 54 in plunger 44 to the lower end of the valve chamber and out through port 59 to the sump 51.

The piston 35 is held to the left in Fig. 5, thereby tightening clutch 14 to provide a high speed drive for spindle 13.

At the same time pressure fluid is conducted from port 49 through passage 55 in plunger 44 to the port 56 leading to the right-hand end of cylinder 30 to effect a drive connection through gear 10 to shaft 12. Fluid is exhausted from the left-hand end of cylinder 30 to port 57 and thence through port 50 to sump 51.

By moving plunger 44 downwardly from the position shown, until flange 58 thereon passes port 57 and flange 59 passes port 56, the fluid pressure is reversed in cylinder 30, while cylinder 34 with its piston remains the same as before.

In this new position fluid pressure passes from port 49 through passage 55 to port 57 and into the left-hand end of cylinder 30 to effect a drive connection through gear 11 to shaft 12. Fluid is exhausted from the right-hand end of cylinder 30 to port 56 and thence through passage 54 to discharge port 50 and sump 51.

Movement of plunger 44 downwardly to the next position causes flange 59 to move to below port 57, and the next flange 60 moves to a location between ports 56 and 57. Flanges 61 and 62 are disposed between ports 53 and 56. Top flange 63 is disposed between ports 49 and 52.

In this position the pistons in both cylinders 30 and 34 are reversed. Fluid pressure passes from port 49 directly through port 53 to the left-hand end of cylinder 34, thereby moving lever 39 to the right, releasing clutch 14 and tightening clutch 23 to provide a low-speed for spindle 13. Fluid is exhausted from the right-hand end of cylinder 34 through port 52, passage 54 and port 50 to the sump 51.

At the same time pressure fluid passes from port 49 through passage 55 and through port 56 to the right-hand end of cylinder 30. This effects movement of piston 31 to the left and operation of clutch 9 to drive shaft 12 by gear 10 on shaft 8. Fluid is exhausted from the left-hand end of cylinder 30 through port 57, passage 54 and port 50 to sump 51.

Movement of plunger 44 downwardly to its next and lowermost position reverses cylinder 30 and clutch 9 while retaining cylinder 34 and clutches 14 and 26 in the position just described.

In the lower position of plunger 44 pressure fluid passes from port 49 through passage 55 to port 57 and thence to the left-hand end of cylinder 30 where it moves piston 31 to the right and effects operation of clutch 9 to drive shaft 12 by gear 11 on shaft 8. Fluid is exhausted from the right-hand end of cylinder 30 through port 56, passage 54 and port 50 to sump 51.

The valve 29 has been described as having four different positions effecting operation of clutches 9, 14 and 26 to produce different speeds for spindle 13. In the first position of plunger 44 shown in Fig. 5, the spindle is driven through high speed gear 10, clutch 9, high speed clutch 14, gears 15 and 16, gear 19 and either gear 20 or 21.

In the second position described the spindle is driven through low speed gear 11, clutch 9, high speed clutch 14, gears 15 and 16, gear 19 and either gear 20 or 21. In the third position described the spindle is driven through high speed gear 10, clutch 9, gears 23 and 24, low speed clutch 26, gears 27 and 28, gears 15 and 16, gear 19 and either gear 20 or 21. In the fourth position described the spindle is driven through low speed gear 11, clutch 9, gears 23 and 24, low speed clutch 26, gears 27 and 28, gears 15 and 16, gear 19 and either gear 20 or 21.

The pump 48 is driven by belt 64 from an auxiliary pulley 65 on the outer end of shaft 8.

Three shafts extend the length of the lathe in front of the bed. Shaft 66 carries gear 46 for operating valve 29 and extends through the turret carriage 67 where it is rotated by suitable control mechanism hereinafter described.

The traverse shaft 68 is driven by suitable belt connections 69 from pulley 65 on shaft 8.

The feed shaft 70 for transmitting feed movement to carriage 67 is driven by chain 71 from the spindle 13.

Turret carriage drive

The feed of the turret carriage by feed shaft 70 is effected by means of a rotary pump-motor unit of high torque and infinitely variable speed within the range of speeds required. A suitable pump-motor combination is illustrated in Figures 8, 9 and 10.

The pump 72 is driven by a sprocket 73 on pump shaft 74, and a chain 75 from sprocket 76 sliding on and keyed to rotate with feed shaft 70. Sprocket 76 is journaled in the carriage 67 and is adapted to move axially along shaft 70 with the carriage 67. The rotation of the pump shaft 74 is thus correlated with and determined by the speed of spindle 13.

The pump 72 receives pressure fluid from pump 48 through conduit 77 extending along the front of bed 1 as shown in Figures 1 and 5. A suitable telescopic connection 78 illustrated in detail in Fig. 7 is provided in conduit 77 to provide for the movement of the pump 72 with turret carriage 67 toward and away from the headstock 3 and pump 48.

The pump 72 is mounted on the front of turret carriage 67 and is preferably of the type set forth in applicant's copending application Serial No. 554,884, filed September 20, 1944, now Patent No. 2,444,159, granted June 29, 1948, for Fluid Pump.

The pump 72 comprises a plurality of adjacent cylinders 79 in which individual pistons 80 are operated by eccentric cam rings 81 on the rotary tubular pump shaft 74. The pistons 80 are biased upwardly by coil springs 82 in the respective cylinders to engage the cam rings 81.

The cam rings 81 are mounted for adjustment eccentrically of shaft 74 by radially extending supports 83, there being a pair of such supports for each ring. The supports 83 extend through the wall of the shaft 74 and engage longitudinally movable cam blocks 84 within the shaft and which hold the corresponding pairs of supports 83 in any desired position relative to the axis of the shaft 74.

Adjustment of blocks 84 axially of the shaft 74 is effected by means of a push rod 85 in the outer end of the shaft and by the springs 86 between the blocks and the rear end spring 87 biasing the blocks outwardly against the push rod. Each block 84 has an axially movable central pin 88 with a head 89 against which the adjoining spring 87 or 86, as the case may be, presses to facilitate holding of the blocks in place and individual adjustment of the same as more fully explained in the copending application referred to.

For any given speed of spindle 13 the pump shaft 74 rotates at a constant speed and effects a given number of strokes of pistons 80 per unit of time. The volume of pressure fluid pumped, however, varies with the stroke of the pistons 80, and the latter is dependent upon the eccentricity of the cam rings 81 on shaft 74.

By pressing push rod 85 inwardly to the position shown in Fig. 8 and beyond the eccentricity of the cam rings 81 can be increased resulting in a corresponding increase in the stroke of pistons 80 and the volume of fluid pumped.

By releasing push rod 85 for outward movement under the influence of the biasing springs 86 and 87, the eccentricity of the cam rings 81 can be reduced resulting in a corresponding decrease in the stroke of pistons 80 and the volume of fluid pumped.

The regulation of the volume of fluid pumped,

by means of push rod 85 can be effected at any time and to any extent during operation of the pump and with substantial accuracy.

The motor 90 is constructed in the same housing as pump 72 and is operated by the fluid pressure from the pump. The motor 90 is preferably of the general type set forth in the copending application of the present inventor, Serial No. 554,883, filed September 20, 1944, now Patent No. 2,471,484, granted May 31, 1949, for Hydraulic Motor.

The motor 90 has its shaft 91 aligned with pump shaft 74 and spring 87 is disposed axially in the hollow shaft 91 to save in space and at the same time provide a long spring of the desired characteristics for operation of the pump. A suitable thrust bearing 92 is provided between spring 87 and the innermost block 84 to take up the differential rotary speeds of the two.

The motor 90 comprises, in general, a plurality of cylinders 93, each containing a piston 94 having a roller 95 engaging a cam member 96 on the shaft 91 to drive the latter.

The cam members 96 are radially disposed at different angles spaced around the axis of shaft 91 so that the pistons 94 have their corresponding operating strokes in succession to provide a substantially continuous drive for the shaft.

Each cam 96 is designed to deliver a uniform rotary torque to shaft 91 proportional to the movement of the corresponding piston during its working stroke. In other words, each increment of upward movement of a piston 94 in its working stroke effects a corresponding increment of rotation of the shaft 91. Equal increments of movement of a piston 94 in its working stroke effect equal increments of rotation of the shaft.

The distribution of power fluid from pump 72 to the respective cylinders 93 of motor 90 is timed by a suitable distributor 97 geared to motor shaft 91.

The exhaust of the motor 90 is returned to sump 51 through conduit 98 which extends parallel to and adjacent the pressure conduit 77 and is similarly constructed.

The speed of motor 90 is dependent upon the volume of liquid pumped by pump 72. The pump 72, being adapted to deliver a predetermined variable quantity of liquid, readily controls the speed of the motor.

The employment of the particular pump-motor unit described has considerable advantage in lathe operations, since it provides an infinite and accurate adjustment of speeds over a wide range and is practically non-stalling. The motor will deliver a substantial torque throughout a wide range of speeds varying from only a fraction of a revolution per minute to over one hundred revolutions per minute.

The motor shaft 91 has a worm gear 99 secured thereon for driving a tubular clutch member 100 mounted to rotate freely on the feed clutch shaft 101 extending transversely of the carriage 67. A second clutch member 102 is keyed to shaft 101 and has an intermediate axially movable clutch member 103 interlocked for rotating the same and adapted to abut the end of member 100 under the biasing influence of springs 104. The abutting ends of clutch members 100 and 103 are toothed to provide a feed clutch so that when they are engaged they effect driving of the shaft 101 by worm gear 99.

Shaft 101 has a pinion 105 on its inner end meshing with a gear rack 106 extending longi-

tudinally on the underside of a flange on bed 1 of the lathe, so that rotation of shaft 101 effects movement of the carriage 67 along the bed. The speed of the feeding movement of carriage 67 is dependent directly upon the speed of motor 90 which in turn depends basically upon the speed of spindle 13 and is controlled or modified by the push rod 85.

Clutch member 103 is pushed axially against springs 104 and out of engagement with the constantly rotating clutch member 100 by means of a piston 107 in a cylinder 108 at the outer end of the housing for shaft 101. The piston 107 carries a rotatable piston rod 109 extending axially into the end of the shaft 101 and which is adapted to abut against a cross member 110 riding in a slot 111 in the shaft and in turn fitting into recesses in the clutch member 103.

A conduit 112 supplies pressure fluid to cylinder 108 from a suitable control valve herein-after described and which receives pressure fluid through conduit 77 from pump 48, to move the piston 107 inwardly in a direction releasing the clutch 103. When the pressure on the piston in cylinder 108 is released and the conduit 112 connected to the sump 51, the springs 104 move clutch 103 into engagement with member 100 and effect driving of shaft 101 by motor 90.

The traverse drive for carriage 67 is effected through a forward and reverse clutch mechanism from the constantly rotating traverse shaft 68, as shown in Fig. 11.

The axially spaced forward and reverse beveled ring gears 113 and 114 are rotatably mounted on a sleeve 115 splined to shaft 68. The gears 113 and 114 mesh with the opposite sides of a beveled gear 116 secured to the lower end of vertical shaft 117. A worm gear 118 secured to the upper end of shaft 117 drives gear 119 and feed shaft 101 to drive the carriage 67 in traverse.

A central clutch member 120 is keyed to sleeve 115 for rotation therewith and axial movement thereon. The member 120 is adapted to clutch ring gear 113 when moved axially toward the same to drive the gear from shaft 68. Likewise, when member 120 is moved axially in the opposite direction it releases ring gear 113 and clutches with ring gear 114 to drive the latter from shaft 68.

The alternate clutching of ring gears 113 and 114 effects the respective forward and reverse traverse drive for the carriage 67 through beveled gear 116, shaft 117, worm gear 118, gear 119, shaft 101 and pinion 105.

Control of clutch 120 is provided by the lever 121 having its upper end pivoted at 122 to the clutch housing and extending as a yoke riding in a circumferential groove in member 120. The lower end of lever 121 extends between two opposed pistons 123 and 124 in the corresponding cylinders 125 and 126.

Conduits 127 and 128 connect to the ends of the corresponding cylinders 125 and 126 to supply pressure fluid thereto for operating the respective pistons 123 and 124.

When conduit 127 is connected to pump 48 through conduit 77 and a suitable valve herein-after described to supply pressure fluid behind piston 123 in cylinder 125, conduit 128 is connected through the valve referred to and conduit 98 to drain fluid from cylinder 126 to sump 51.

This results in movement of lever 121 to the right and engagement of clutch 120 with gear 114 to drive the same from shaft 68.

When conduit 128 is connected to pump 48

75

through the valve referred to and conduit 77 to supply pressure fluid behind piston 124 in cylinder 126, conduit 127 is connected to drain fluid from cylinder 125 through the valve referred to and conduit 98 to sump 51. This results in movement of lever 121 to the left and engagement of clutch 120 with gear 113 to drive the same from shaft 68.

The control valve 129 for controlling the supply of pressure fluid to cylinders 108, 125 and 126 is shown in Fig. 15.

The control valve 129 is of the piston type and comprises a valve body 130 having a cylindrical main valve chamber 131 with a central inlet port 132 for pressure fluid from pump 48 and an end discharge port 133 for fluid return to sump 51, and a cylindrical routing valve chamber 134 with three longitudinally spaced ports 135, 136 and 137 in its side.

Port 135 connects with conduit 127 leading to cylinder 125, port 136 connects with conduit 112 leading to cylinder 108, and port 137 connects with conduit 128 leading to cylinder 126.

The chambers 131 and 134 are disposed side by side and have two longitudinally spaced ports 138 and 139 connecting the same through the common side wall thereof.

A main valve plunger 140 is reciprocably disposed in chamber 131 and has four flanges fitting the inside walls of the chamber and providing a wide central circumferential inlet groove 141 and two end circumferential discharge grooves 142 and 143, respectively. The discharge grooves 142 and 143 are connected by ports 144 to a longitudinal passage 145 in plunger 140 and which opens to the right-hand end of chamber 131 from which port 133 drains to the sump 51 through conduit 98.

When plunger 140 is in its central position, as shown in Fig. 15, which is the feed position for carriage 67, the central groove 141 is closed, and ports 138 and 139 communicate with the corresponding grooves 142 and 143 and effect discharge into sump 51 from both ends of routing valve chamber 134.

When plunger 140 is moved to the left, to back traverse position, the central groove 141 connects inlet port 132 with port 138 to supply pressure fluid to the left-hand end of chamber 134, and at the same time end groove 143 connects port 139 to the discharge port 133 and sump 51.

When plunger 140 is moved to the right, to the forward traverse position, the central groove 141 connects inlet port 132 with port 139 to supply pressure fluid to the right-hand end of chamber 134, and at the same time end groove 142 connects port 138 to the discharge port 133 and sump 51.

The routing valve plunger 146 has a central piston member 147 fitting in the valve chamber 134 between ports 138 and 139 to serve as the motivating means for reciprocating the plunger under the influence of the pressure fluid admitted through either port 138 and 139.

When pressure fluid is admitted to chamber 134 through port 138 it forces piston 147 to the right until it uncovers the ports 135 and 136 to expose the same to the pressure fluid through port 138. The end of the plunger 146 engages the end of chamber 134 and limits the movement of piston 147 to the right, thereby retaining an open connection for drainage of fluid from cylinder 126 through conduit 128, port 137, port 139, and port 133 to sump 51.

In this latter position of piston 147 pressure

fluid is admitted to cylinder 108 through ports 138 and 136 and conduit 112, thereby opening clutch 103 to disconnect motor 90 from feed shaft 101. At the same time pressure fluid is admitted to cylinder 125 through ports 138 and 135 and conduit 127 to push piston 123 and move lever 121 to the right, thereby effecting back traverse drive for carriage 67 through gear 114.

When pressure fluid is admitted to chamber 134 through port 139 it forces piston 147 to the left until it uncovers the ports 136 and 137 to expose the same to the pressure fluid through port 139. The end of plunger 146 engages the end of chamber 134 and limits the movement of piston 147 to the left, thereby retaining an open connection for drainage of fluid from cylinder 125 through conduit 127, port 135, port 138 and port 133 to sump 51.

In this latter position of piston 147 pressure fluid is admitted to cylinder 108 through ports 139 and 136 and conduit 112, thereby opening clutch 103 to disconnect motor 90 from feed shaft 101. At the same time pressure fluid is admitted to cylinder 126 through ports 139 and 137 and conduit 128 to push piston 124 and move lever 121 to the left, thereby effecting forward traverse drive for carriage 67 through gear 113.

When the main valve plunger 140 is moved to central position to cut off pressure fluid from both ports 138 and 139, as shown in Fig. 15, the ports 138 and 139 register with the corresponding grooves 142 and 143 and serve to connect all of the cylinders 108, 125 and 126 to sump 51, thereby allowing clutch 103 to engage member 100 and effect feeding of carriage 67 by motor 90, while lever 121 drops to central position where both the forward and reverse clutches are open.

The main plunger 140 is operated by an axial piston rod 148 extending through the end of valve body 130. A manual lever arm 149 is secured on the front of the carriage 67 adjacent valve 129 and turns a shaft 150 having an upwardly extending forked arm 151 engaging a cross pin 152 in the outer end of rod 148 to operate the latter.

Since the cylinders 125 and 126 are below the level of sump 51 and of control valve 129, a small scavenger pump 153 is provided in the housing for the forward and back traverse clutch and is operated by an eccentric 154 on the sleeve 115 to facilitate the return of fluid from the cylinders to the sump.

The automatic control mechanism

The automatic control of the various movements, including the spindle speed, traverse and feed of the turret carriage and the traverse and feed of the tool post, is provided by a cam drum 155 mounted on the front of bed 1 and extending longitudinally between a forward bracket 156 near the tool post carriage 157 and the rear end housing 158 for the indexing mechanism.

The cam drum 155 extends longitudinally adjacent the path of movement of carriage 67 and has six sides corresponding to the six sides of turret 5 which is mounted on the carriage. Each side of the drum 155 has a set of cam strips and stops for controlling all of the lathe operations necessary for performing the machining operations corresponding to the tools on the particular face of the turret 5, both the turret 5 and the drum 155 being indexed simultaneously and in direct correlation with each other.

Referring to a single face of the cam drum 155, there are two grooves 159 and 160 extending

longitudinally of the drum and in which the several cam strips and stops are adjustably secured by split expansion clamps 161, as shown in Fig. 13.

5 A wiper cam trip 162 is secured near the rear end of the drum for engaging a depending projection 163 on a plate 164 secured to shaft 150 to turn the latter and lever 149 to forward traverse position as the cam drum 155 turns to index the particular face.

10 As the carriage 67 moves forwardly in traverse, a cam follower 165 engages and rides on top of a cam strip 166 clamped against the forward side of groove 160 and which has a predetermined height.

15 The cam follower 165 supports a vertical rack 167 which operates a cross rack 168 by pinion 169. The cross rack 168 meshes with a pinion 170 on shaft 66 which operates the control valve 20 29 at the front of the headstock 3 to set and maintain the spindle speed as represented by the height of cam strip 166.

25 The cam 171 clamped against the back side of groove 160 has an offset lip which engages the rear descending projection 172 on plate 164 to swing shaft 150 and lever 149 to center feed position as the carriage reaches the position for stopping the forward traverse and commencing the forward feed. From that point on the carriage 67 moves forward at the predetermined feed rate.

30 When the carriage reaches the forward end of its feed a second cam 173 offset in the opposite direction from cam 171 abuts against the projection 163 to swing the shaft 150 and lever 149 to back traverse position. As the carriage returns rearwardly in back traverse movement projection 163 on plate 164 misses the offset cam 171, since projection 163 is laterally offset from projection 172, as shown in the drawing.

35 The rate of feed for carriage 67 is primarily determined by the spindle speed as previously described, and secondarily determined by the volume of pressure fluid supplied to motor 90 from pump 72 as regulated by the push rod 85.

40 The position of push rod 85 during feeding of the carriage is determined and regulated by cam strip 174 clamped against the front side of groove 159 and upon which the cam follower 175 rides.

45 The cam follower 175, when riding on strip 174 supports the vertical rack 176 which meshes with a gear 177 rotatably mounted on a pivot shaft 178.

50 The other side of the gear 177 diametrically opposite the rack 176 meshes with a gear segment 179 on a rocker arm 180 carried by a rock shaft 181 journaled in a bracket 182 on the forward end of the housing for pump 72.

55 A second rocker arm 183 integral with the rock shaft 181 extends upwardly and carries at its end an adjustable abutment screw 184 threaded therethrough and axially pressing against the push rod 85.

60 The higher cam strip 174 is, the farther will abutment 184 push the rod 85 inwardly of the pump and the greater will be the volume of pressure fluid supplied to the motor 90.

65 The cam strip 185 clamped against the back of groove 159 controls the feed for the tool post 4.

In the present embodiment the tool post 4 is mounted on a cross slide 186 which in turn is mounted on the tool post carriage 157, and cam strip 185 controls the feed of the cross slide.

70 A follower 187 rides on strip 185 and grad-

ually raises a vertical rack 188 meshing with a gear segment 189 having trunnions 190 journaled in bearings 191 in the bottom of the housing for pump 72.

A second gear segment 192 diametrically opposite segment 189 and disposed on a longer arm 193, meshes with a gear 194 keyed upon shaft 195 to rotate the latter.

The shaft 195 is journaled in carriage 67 and extends forwardly through the tool post carriage 157 where it slides through a sprocket 196 which is keyed to it to rotate therewith.

A chain 197 drives a sprocket 198 on the tool post carriage 157 from sprocket 196 on shaft 195. The sprocket 198 in turning in one direction drives the plunger of control valve 199 for admitting pressure fluid to one end of power cylinder 200 to feed cross slide 186 inwardly. Turning of the sprocket 198 in the opposite direction drives the control valve plunger in the opposite direction for admitting pressure fluid to the opposite end of power cylinder 200 and gradually withdraws the cross slide. The pressure fluid for operating power cylinder 200 is supplied by conduit 77 through take-off block 201 and is similarly returned to the sump by conduit 98.

Various types of drive may be provided for feeding cross slide 186. It is preferred to employ a servo-motor construction for valve 199 and power cylinder 200, such as that set forth in copending application Serial No. 608,985, filed August 4, 1945, by the present inventor.

The longitudinal movement of the tool post carriage 157 is also controlled by drum 155. For this purpose a segmented cam ring 202 is provided on the right hand end of drum 155 for engaging the lever arm 203 of a limit switch 204.

When a segment of ring 202 raises the arm 203 the switch is operated to effect operation of the solenoid cross-over valve 205 which controls the supply of pressure fluid from pump 48 to a cylinder 206 secured to the front of the headstock 3.

A piston 207 in cylinder 206 has a rod 208 extending longitudinally and secured to the carriage 157.

When the switch arm 203 is raised by cam ring 202, the valve 205 is operated to admit pressure fluid to the left end of cylinder 206 and to exhaust fluid from the right end of the cylinder, thereby moving carriage 157 to the right until an adjustable stop 209 locates it for operation of the cross slide.

When the switch arm 203 is allowed to fall, the valve 205 is operated to admit pressure fluid to the right end of cylinder 206 and to exhaust fluid from the left end of the cylinder, thereby moving carriage 157 to the left until the piston 207 reaches the end of the cylinder.

The segments of the cam ring 202 will be disposed to actuate switch arm 203 to retract the tool post carriage at such times as the tool post should remain inactive, as for instance during loading and unloading of the lathe or during machining operations by the turret 5 corresponding to a particular face of the cam drum 155 where tool post machining is not to be employed. In all other positions the switch 204 effects forward positioning of the carriage where the tool post can be employed.

A second limit switch 210 constitutes the stop button for the lathe and automatically controls the stopping of motor 6.

The switch 210 is located adjacent switch 204 and has an arm 211 actuated by a button 212 on

drum 155 to stop motor 6 when the complete machining cycle is finished and the drum 155 is indexing to a starting position for the next succeeding machining cycle.

A manual start and emergency stop switch 213 is provided on the front of headstock 3. In addition, an emergency stop manually operable bypass valve 214 for stopping the feed of the carriage 67 is provided on the front of the carriage.

Turret and control drum indexing

The mechanism for indexing the turret 5 and the cam drum 155 is disposed in the index housing 158 at the rear end of the bed 1 and comprises, in general, a normally open clutch tripped to closed position by the rearward return of carriage 67 and adapted to effect a predetermined simultaneous rotation of the turret and of cam drum from the constantly rotating traverse shaft 68 to present the next working face of the turret and the corresponding control face of the drum.

Various types of clutches may be employed, the clutch illustrated comprising a beveled gear 215 freely rotating on a transverse shaft 216 and driven by a gear 217 on the rear end of traverse shaft 68, an axially movable clutch member 218 keyed on shaft 216 and adapted to move toward gear 215 and effect a positive interlock with a spring backed pin 219 extending from the face of the body of the gear and which enters a recess 220 in the face of the clutch member 218, to drive the shaft 216 from gear 215.

The mechanism for moving the clutch 218 into engagement comprises a bell crank lever 221 pivoted on a vertical stud 222 secured in the bottom of housing 158. One arm of the lever 221 extends at right angles to the shaft 216 beneath the same and has an upwardly extending pin 223 at its end riding in a circumferential groove 224 in clutch member 218. The other arm of lever 221 extends to the left in Figs. 17 and 18 and has pivotally secured thereto a pusher arm 225 normally extending forwardly of the lathe in alignment with a hole 226 through the front wall of housing 158.

A trip pin 227 is carried by carriage 67 in line with hole 226 and is adapted to move axially against a holding spring 228 on the carriage to allow the carriage to continue in its rearward traverse movement after pin 227 engages pusher arm 225.

The engagement of pusher arm 225 by pin 227 as the latter comes through hole 226 effects operation of the bell crank lever 221 in a direction causing closing of the clutch 218 and driving of shaft 216 by gear 215.

The shaft 216 effects rotation of the turret 5 for indexing the latter by means of the beveled gear 229 at the right end of the shaft driving vertical shaft 230 which in turn is geared to drive the turret index shaft 231.

The shaft 216 also effects rotation of drum 155 for indexing the latter by means of the worm gear 232 at the left end of the shaft meshing with gear 233 on the end of a stub shaft 234 supporting the drum.

When the turret 5 and drum 155 have been rotated to their next working position the clutch 218 is disengaged by a trip mechanism comprising a wheel 235 on shaft 234 and having a dog 236 secured thereon for engaging an adjustable screw 237 in a hanging post 238 to swing the latter against pusher arm 225 thereby releasing the latter from the end pressure of pin 227.

Spring 239 then returns bell crank lever 221 to its normal position opening the clutch.

The small lateral movement of pusher arm 225 under pressure from post 238 for releasing pin 227, is provided by a lost motion pivotal connection between arm 225 and the end of bell crank lever 221. A spring 240 retains the pusher arm 225 in normal alignment with pin 227.

Where the drum and turret are to be indexed at each successive face there will be a dog 236 disposed on wheel 235 for each face. In case it is desired to skip one or more working faces, the dog or dogs corresponding to the same are removed, thereby allowing the clutch to continue closed and to rotate the shaft 216 until a dog 236 engages contact 237 and trips the clutch disengaging mechanism. In this event the wiper cam 162 corresponding to the omitted dog 236 is also omitted to avoid tripping lever 149 to forward traverse position as the drum 155 passes the index position.

A lost motion connection is provided between drum 155 and shaft 234 by means of a loose key 241.

A spring-backed locking pin 242 is disposed in a cylinder 243 attached to the front side of housing 158 and is directed radially toward the end member 244 of drum 155.

Member 244 has a series of angular recesses 245 therein which are accurately located relative to the corresponding faces of the drum so that when pin 242 enters a given recess it locks the drum in position for the corresponding face to be operative in controlling the cycle of the lathe.

The shape of the recesses 245 is such that when pin 242 starts into a recess it gives a quick forward rotary acceleration to the drum which effects positive location of pin 242 at the bottom of the recess and accurate indexing and in addition effects a quick wiping action of trip 162 past projection 163 to start the forward traverse of carriage 67.

Where a stop rod 246 is employed for turret carriage 67, it is indexed along with the turret 5 and control drum 155 by means of chain 247 driven from sprocket 248 on shaft 234.

Operation of the lathe

Summarizing the operation of the lathe, when a blank has been chucked on the end of spindle 13 switch button 213 is pushed to start motor 6 which drives headstock 3, traverse shaft 68, feed shaft 70 and pump 48.

The lever 149 is either in forward traverse position, by reason of the wiping action of cam 162 upon the last indexing of drum 155, or it can be manually moved to forward traverse position, and the forward traverse clutch drives carriage 67 forwardly.

When cam follower 165 engages and rides upon cam strip 166 the plunger 44 for control valve 29 is operated to shift clutches 9, 14 and 26 in headstock 3 to provide the required speed for spindle 13.

When the carriage reaches the position for commencement of its forward feed cam 171 on drum 155 engages dog 172 to swing lever 149 to feed position, thereby disengaging the forward traverse clutch and engaging the feed clutch 103 to effect feed of the carriage at a rate determined by the spindle speed and by the additional superimposed control of pump 72 and motor 90.

Follower 175 riding on cam strip 174 effects a continuous control of the displacement of pump

72 as the carriage 67 moves forwardly driven by motor 90.

In the meantime, limit switch 204 is moved by cam segment 202 to operate solenoid valve 205 and effect longitudinal movement of the tool post carriage 151 to its rear position. As carriage 67 moves forwardly, follower 187 rides slowly upwardly on cam 185 to regulate the servomotor on carriage 157 and feed the cross slide 186 and its tool post 4 to the work.

When the carriage 67 reaches the forward end of its intended feed, the cam 173 abuts dog 163 and trips lever 149 to back traverse position, engaging the back traverse clutch and disengaging feed clutch 103.

The carriage 67 continues in its back traverse movement until dog 163 engages a radially extending cam portion of wiper cam 162 and is lifted thereby to swing lever 149 to feed position. At this time pin 227 engages pusher arm 225 and causes the clutch member 218 to engage and effect indexing of turret 5 and drum 155 to the next face, whereupon the next successive wiper cam 162 on drum 155 trips lever 149 to forward traverse position for the carriage 67.

When all of the operations have been completed and the work piece is to be removed, the button 212 operates limit switch 210 to stop the lathe.

The complete cycle of operation of the lathe involves loading, starting the main motor and the forward traverse of the turret carriage followed by forward feed and final back traverse corresponding to the first indexed position of the turret, the indexing of the turret and of the cam control drum to each succeeding working position followed in each instance by the forward traverse, feed and back traverse of the carriage until all of the machining operations have been completed, stopping of the main motor, and unloading. The cycle further involves the moving of the tool post carriage to and from position and each indexed position of the turret calls for the setting of the spindle speed, the control of the turret carriage feed, and the control of the tool post cross slide feed.

The invention provides many features of advantage in the construction of an automatic turret lathe. The employment of a pump-motor unit of the class described for feeding the carriage or any other tool supporting member provides a wide range of speeds from a very slow speed up to a maximum without variations in torque for a given load. It also provides a simple and easily maintained mechanism for varying the feed rate in correlation with the carriage movement.

The employment of a rotary hydraulic motor for feeding purposes provides a smoother and more constant feeding motion and better eliminates any tendency to chatter as in the case of large single pistons employed for feeding operations, particularly where a considerable amount of power is required over a long movement as in the feeding of a turret carriage.

The employment of a master control drum mounted on the bed instead of on the carriage and interengaging with members on the moving carriage permits the use of a longer drum with more accurate cams and adjustable placement of the cams longitudinally of the drum for instantaneous control of each function of the lathe in accurate correlation with the movement and position of the carriage at all times.

The employment of a single hydraulic power

15

system for carrying out the several control functions greatly simplifies the control and enables the employment of individual cam members to control each function in proper correlation and sequence and without interfering with any of the other functions.

The employment of an indexing mechanism in the rear end housing provides an accurate common index for the turret, the control drum and the stop rod, and locates the mechanism for ready repair and maintenance.

Various embodiments of the several features of the invention may be employed within the scope of the accompanying claims.

I claim:

1. In a lathe or the like, a tool carrying member requiring feeding movement over a substantial length of travel at a selected speed within a wide range of speeds in which the maximum speed is in excess of one hundred times the minimum speed, a hydraulic positive displacement motor disposed to drive the member at any selected speed throughout the range of speeds by variation in speed of the motor, said motor comprising a motor shaft, a plurality of cylinders with corresponding pistons for successively transmitting torque to said shaft, and cam members on the shaft disposed to translate the reciprocal movement of the pistons into a substantially constant rotary movement of the shaft with substantially equal increments of rotation of the shaft for corresponding equal increments of movement of each of the pistons in the respective power strokes thereof, and said motor having a uniform torque output for a selected uniform throughput of power liquid and being governed in speed by the volume of power liquid passing therethrough, means to feed said member from said motor shaft, separate alternative means to traverse said member forward and back and means disposed to selectively vary and constantly control the volume of power liquid supplied to said motor in correlation to the travel of said tool member.

2. In a lathe or the like, a tool carrying member requiring feeding movement over a substantial length of travel at a selected speed within a wide range of speeds in which the maximum speed is in excess of one hundred times the minimum speed, means to traverse said members forward and backward, a motor-pump unit for driving the member at feed and semi-traverse rates and comprising, a rotary motor shaft disposed to drive the member, a plurality of cylinders with corresponding pistons for successively transmitting torque to said shaft, cam members on the shaft disposed to translate the reciprocal movement of the pistons into rotary movement of the shaft with substantially equal increments of rotation of the shaft for corresponding equal increments of movement of each of the pistons in the respective power strokes thereof, said motor having a uniform torque output for a selected uniform throughput of power liquid and being governed in speed by the volume of power liquid passing therethrough, a variable displacement pump adapted to deliver to said motor a selected volume of power liquid, and means to regulate the displacement of said pump to select and regulate the speed for said member in correlation to the travel of the tool member.

3. In a lathe or the like, a tool carrying member requiring feeding movement at a selected speed within a wide range of speeds in which the maximum speed is in excess of one hundred

16

times the minimum speed, and a motor-pump unit carried by said member for driving the same and comprising, a rotary motor shaft disposed to drive the member, a plurality of cylinders with corresponding pistons for successively transmitting torque to said shaft, cam members on the shaft for translating the reciprocal movement of the pistons into rotary movement of the shaft with substantially equal increments of

10 rotation of the shaft for corresponding equal increments of movement of each of the pistons in the respective power strokes thereof, a variable displacement pump adapted to deliver to said motor a selected volume of power liquid, means

15 to supply liquid under a substantially constant initial pressure to said pump, and cam means coordinated with the movement of said member and disposed to regulate the displacement of said pump and thereby select the speed for said member.

4. In a lathe or the like, a tool carrying member requiring feeding movement at a selected speed within a wide range of speeds in which the maximum speed is in excess of one hundred

25 times the minimum speed, and a motor-pump unit for driving the same and comprising, a rotary motor shaft disposed to drive the member, a plurality of cylinders with corresponding pistons for successively transmitting torque to

30 said shaft, cam members on the shaft for translating the reciprocal movement of the pistons into rotary movement of the shaft, a rotary pump shaft, a plurality of adjustable cam members secured on said shaft, a plurality of pistons

35 driven by corresponding cams on said shaft and operating in individual cylinders for pumping pressure fluid to said motor, means to drive said pump shaft at a predetermined speed, and means correlated with the advance of said tool carrying member and disposed to adjust said cams on said pump shaft and thereby determine the displacement of said pump to select the speed for said member.

5. In a lathe or the like, a tool carrying mem-

45 ber requiring feeding movement at a selected speed within a wide range of speeds in which the maximum speed is in excess of one hundred times the minimum speed, and a motor-pump unit carried by said member for driving the same and comprising, a rotary motor shaft disposed to drive the member, a plurality of cylinders with corresponding pistons for successively trans-

50 mitting torque to said shaft, cam members on the shaft for translating the reciprocal move-
55 ment of the pistons into rotary movement of the shaft, a rotary pump shaft, a plurality of adjustable cam members secured on said shaft, a plurality of pistons driven by corresponding cams on said shaft and operating in individual cylinders

60 for pumping pressure fluid to said motor, and means correlated with the advance of said tool carrying member and disposed to adjust said cams on said pump shaft and thereby determine the displacement of said pump to select the speed for said member.

6. In a lathe or the like, a headstock having a rotary spindle, a tool carrying member requiring feeding movement at a selected speed within a wide range of speeds, and a motor pump-unit

70 for driving the same and comprising, a rotary motor shaft disposed to drive the member, a plurality of cylinders with corresponding pistons for successively transmitting torque to said shaft, cam members on the shaft for translating the reciprocal movement of the pistons into

rotary movement of the shaft, a rotary pump shaft, a plurality of adjustable cam members secured on said shaft, a plurality of pistons driven by corresponding cams on said shaft and operating in individual cylinders for pumping pressure fluid to said motor, means to drive said spindle at a selected rate, means correlated with said spindle drive to drive said pump shaft at a speed determined by said selected spindle speed, and means correlated with the advance of said tool carrying member to vary the eccentricity of said cams on the pump shaft for determining the displacement of said pump and thereby selecting the feed for said member.

7. In a lathe having a rotary spindle carrying a workpiece, a tool carrying member adapted to be fed relative to the work, a hydraulic motor feed for said member, a servo control valve operable by the movement of said member and connected to control the supply of power fluid to said motor, a turret carriage for said lathe, a cam disposed parallel to and adjacent the path of movement of said turret carriage, a cam follower on said turret carriage riding on said cam, and a control rod disposed to actuate said servo valve in response to said cam follower to provide a variable and selected rate of feed for said tool carrying member correlated to the movement of the carriage.

8. An automatic turret lathe comprising a bed, a reciprocating carriage on said bed adapted to have traverse movement in both directions of reciprocation and feed movement in at least one direction of reciprocation, a turret mounted on said carriage and adapted to be successively indexed to predetermined selected positions, a master control drum on said bed adapted to be indexed in correlation to the indexing of the turret, means disposed to feed said carriage, separate means disposed to traverse the carriage, clutch mechanism disposed to selectively connect the feed and traverse drives and to selectively reverse the latter, and inter-engaging cam means on said drum and carriage disposed to select and regulate said carriage feed in correlation to the movement of the carriage and to operate said clutch.

9. An automatic turret lathe comprising a bed, a headstock having a rotary spindle, means in said headstock for driving said spindle at a selected speed, a reciprocating carriage on said bed adapted to have traverse movement in both directions of reciprocation and feed movement in at least one direction of reciprocation, a turret mounted on said carriage and adapted to be successively indexed to selected positions, a master control drum on said bed, means disposed to index said drum in correlation to the indexing of the turret, means disposed to feed said carriage from said headstock at a speed correlated to the selected spindle speed, separate means disposed to traverse the carriage, clutch mechanism on said carriage disposed to connect the feed and forward and reverse traverse drives selectively, inter-engaging means on said drum and carriage operable initially by the indexing of the drum and thereafter by movement of the carriage relative to the drum to actuate said clutch mechanism and initiate and determine said feed and traverse carriage movements in correlation to the indexed position of the turret.

10. An automatic turret lathe comprising a bed, a headstock having a rotary spindle, means in said headstock for driving said spindle at a selected speed, a reciprocating carriage on said

bed adapted to have traverse movement in both directions of reciprocation and feed movement in at least one direction of reciprocation, a turret mounted on said carriage and adapted to be successively indexed to selected positions, a master control drum on said bed, means disposed to index said drum in correlation to the indexing of the turret, means disposed to feed said carriage from said headstock at a speed correlated to the selected spindle speed, separate means disposed to traverse the carriage, clutch mechanism on said carriage disposed to connect the feed and forward and reverse traverse drives selectively, inter-engaging means on said drum and carriage operable initially by the indexing of the drum and thereafter by movement of the carriage relative to the drum to actuate said clutch mechanism and initiate and determine said feed and traverse carriage movements in correlation to the indexed position of the turret, and inter-engaging means on said drum and carriage disposed to select the spindle speed in said headstock in response to forward movement of the carriage relative to the drum and in correlation to the indexed position of said turret.

11. An automatic turret lathe comprising a bed, a headstock having a rotary spindle, means in said headstock for driving said spindle at a selected speed, a reciprocating carriage on said bed adapted to have traverse movement in both directions of reciprocation and feed movement in at least one direction of reciprocation, a turret mounted on said carriage and adapted to be successively indexed to selected positions, a master control drum on said bed, means disposed to index said drum in correlation to the indexing of the turret, means disposed to feed said carriage from said headstock at a speed correlated to the selected spindle speed, separate means disposed to traverse the carriage, clutch mechanism on said carriage disposed to connect the feed and forward and reverse traverse drives selectively, inter-engaging means on said drum and carriage operable initially by the indexing of the drum and thereafter by movement of the carriage relative to the drum to actuate said clutch mechanism and initiate and determine said feed and traverse carriage movements in correlation to the indexed position of the turret, inter-engaging means on said drum and carriage disposed to select the spindle speed in said headstock in response to forward movement of the carriage relative to the drum and in correlation to the indexed position of said turret, and additional inter-engaging cam means on said drum and carriage disposed to regulate said carriage feed in correlation to the movement of the carriage.

12. An automatic turret lathe comprising a bed, a headstock having a rotary spindle, means in said headstock for driving said spindle at a selected speed, a reciprocating carriage on said bed adapted to have traverse movement in both directions of reciprocation and feed movement in at least one direction of reciprocation, a turret mounted on said carriage and adapted to be successively indexed to selected positions, a master control drum on said bed adapted to be indexed in correlation to the indexing of the turret and carrying a separate set of control cams and trips for each index face of said turret, means disposed to feed said carriage from said headstock at a speed correlated to the selected spindle speed, separate means disposed to traverse the carriage, clutch mechanism on said carriage disposed to connect the feed and for-

ward and reverse traverse drives selectively, inter-engaging cam trip members on said drum and carriage disposed to operate said clutch mechanism initiating and determining said feed and traverse carriage movements in correlation to the indexed position of the turret, inter-engaging cam members on said drum and carriage disposed to select the spindle speed in said headstock in correlation to the indexed position of said turret, and additional inter-engaging cam members on said drum and carriage operative during forward movement of the carriage to regulate said carriage feed in correlation to the movement of the carriage.

13. In an automatic lathe, a bed, a reciprocating turret carriage on said bed, a tool post carriage on said bed, a slide for said tool post carriage, a tool post mounted on said slide, a master control drum on said bed adjacent said turret carriage, means for driving said turret carriage, means disposed to index said drum in correlation to the indexing of the turret, means on said tool post carriage disposed to operate said slide at a variable speed, and inter-engaging means on said drum and turret carriage connected to said last named means and operable in response to forward movement of the turret carriage relative to the drum to pre-select the feed of said slide in correlation with the indexing of the turret.

14. In an automatic lathe, a bed, a reciprocating turret carriage on said bed, a tool post carriage on said bed, a slide for said tool post carriage, a tool post mounted on said slide, means for driving said turret carriage, means on said tool post carriage disposed to operate said slide at a variable speed, and means disposed between the bed and turret carriage to be responsive to the movement of said turret carriage along the bed and connected to said last named means to regulate the feed of said slide in correlation to the movement of said turret carriage.

15. In an automatic lathe, a bed, a reciprocating turret carriage on said bed, a turret mounted on said carriage and adapted to be successively indexed to selective positions, a tool post carriage on said bed, a slide for said tool post carriage, a tool post mounted on said slide, means disposed to drive said turret carriage, means on said tool post carriage disposed to operate said slide at a variable speed, a plurality of sets of means disposed between the bed and turret carriage to be responsive to the movement of said turret carriage along the bed and connected to said last named means to regulate the feed of said slide in correlation to the movement of said turret carriage, and means operable in correlation to the indexing of said turret to present a separate set of control means responsive to the movement of said turret carriage for each corresponding index face of the turret.

16. In an automatic lathe, a bed, a reciprocating turret carriage on said bed, a turret mounted on the carriage and adapted to be successively indexed to selected positions, a master control drum on said bed and indexed in correlation to the indexing of the turret, a tool carriage on said bed, a slide for said tool carriage with a tool post thereon, means for driving said turret carriage, means on said tool post carriage for operating said tool post slide at a variable speed, inter-engaging means on said drum and turret carriage controlling the feed

of said turret carriage in correlation to the indexed position of said drum, and additional inter-engaging means on said drum and turret carriage connected to said tool post slide operating means for controlling the feed of said slide in correlation to the feed of said turret carriage.

17. In an automatic lathe, a bed, a reciprocating carriage on said bed adapted to have traverse movement in both directions of reciprocation and feeding movement in at least one direction of reciprocation, means disposed to feed said carriage, separate means disposed to drive said carriage in traverse, clutch mechanism on said carriage disposed to connect the feed and forward and reverse traverse drives selectively, a tool post slide with a tool post thereon, means disposed to drive said tool post slide at a variable speed, a master control drum on said bed, and separate inter-engaging means on said drum and carriage disposed to operate said clutch mechanism and said slide feed in correlation with each other for machining operations.

18. In an automatic lathe, a bed, a reciprocating carriage on said bed adapted to have traverse movement in both directions of reciprocation and feeding movement in at least one direction of reciprocation, means disposed to feed said carriage, separate means disposed to drive said carriage in traverse, clutch mechanism on said carriage disposed to connect the feed and forward and reverse traverse drives selectively, a tool post slide with a tool post thereon, means disposed to drive said tool post slide at a variable speed, a set of cam control members on said bed adjacent the path of movement of said carriage, and control members on said carriage adapted to engage corresponding cam members and effect correlated operation of said clutch mechanism and of said slide feed.

19. In an automatic turret lathe, a bed, a reciprocating carriage on said bed adapted to have traverse movement in both directions of reciprocation and feed movement in at least one direction of reciprocation, a turret mounted on said carriage and adapted to be successively indexed to predetermined selected positions, means disposed to feed said carriage, separate means disposed to traverse the carriage, clutch mechanism on said carriage disposed to connect the feed and forward and reverse traverse drives selectively, a tool post carriage on said bed, a slide for said tool post carriage with a tool post mounted thereon, means disposed to operate said slide at a variable speed, a master control drum on said bed and indexed in correlation to the indexing of said turret, and inter-engaging means on said drum and turret carriage disposed to operate said clutch mechanism to initiate and determine said feed and traverse carriage movements and connected to said slide operating means for controlling said slide movements in correlation to the indexed position of the turret.

20. In an automatic turret lathe, a bed, a reciprocating carriage on said bed adapted to have traverse movement in both directions of reciprocation and feed movement in at least one direction of reciprocation, a turret mounted on said carriage and adapted to be successively indexed to predetermined selected positions, means disposed to feed said carriage, separate means disposed to traverse the carriage, clutch mechanism on said carriage disposed to connect the feed and traverse drives selectively, a tool post carriage on said bed, a slide for said tool post

carriage with a tool post mounted thereon, means disposed to operate said slide at a variable speed, a master control drum on said bed and indexed in correlation to the indexing of said turret, and inter-engaging means on said drum and turret carriage disposed to operate said clutch mechanism to thereby initiate and determine said feed and traverse carriage movements and additionally disposed to regulate the carriage feed and slide movements in correlation to the movement of the carriage.

21. In an automatic turret lathe, a bed, a reciprocating carriage on said bed adapted to have traverse movement in both directions of reciprocation and feed movement in at least one direction of reciprocation, a turret mounted on said carriage and adapted to be successively indexed to predetermined selected positions, means disposed to feed said carriage, separate means disposed to traverse the carriage, clutch mechanism on said carriage disposed to connect the feed and traverse drives selectively, a tool post carriage on said bed, a slide for said tool post carriage with a tool post mounted thereon, means disposed to operate said slide at a variable speed, a plurality of sets of cam control members disposed adjacent the path of movement of said turret carriage with means for indexing a separate set of said cam members in operative position for each corresponding indexed position of said turret, and control members on said turret carriage operated by said indexed set of cam members to control the operation of said clutch mechanism to thereby initiate and determine said feed and traverse carriage movements and disposed to regulate the carriage feed and slide feed movements in correlation to the movement of the carriage.

22. An automatic turret lathe comprising a bed, a headstock having a rotary spindle, means in said headstock for driving said spindle at a speed selected from a group of predetermined speeds, a reciprocating turret carriage on said bed adapted to have traverse movement in both directions of reciprocation and feed movement in at least one direction of reciprocation, a turret mounted on said carriage and adapted to be successively indexed to predetermined selected positions, means disposed to feed said turret carriage from said headstock at a speed correlated to the selected spindle speed, separate means disposed to traverse the turret carriage, clutch mechanism on said carriage disposed to connect the feed and traverse drives selectively, a tool post carriage on said bed, a slide for said tool post carriage with a tool post mounted thereon, means disposed to operate said slide at variable speeds, a master control drum on said bed and indexed in correlation to the indexing of the turret, and separate inter-engaging means on said drum and turret carriage disposed to control the operation of said clutch mechanism to thereby initiate and determine said feed and traverse carriage movements, disposed to select the spindle speed in said headstock and disposed to control the movement of said slide in correlation to the indexed position of the turret.

23. An automatic turret lathe comprising a bed, a headstock having a rotary spindle, means in said headstock for driving said spindle at a speed selected from a group of predetermined speeds, a reciprocating turret carriage on said bed adapted to have traverse movement in both directions of reciprocation and feed movement in at least one direction of reciprocation, a turret mounted on said carriage and adapted to be successively

indexed to predetermined selected positions, means disposed to feed said turret carriage from said headstock at a speed correlated to the selected spindle speed, means disposed to vary the feed of said turret carriage during movement thereof, separate means disposed to traverse the turret carriage, clutch mechanism on said carriage disposed to connect the feed and traverse drives selectively, a tool post carriage on said bed, a slide for said tool post carriage with a tool post mounted thereon, means disposed to operate said slide at variable speeds, a master control drum on said bed and indexed in correlation to the indexing of the turret, and separate inter-engaging means on said drum and turret carriage disposed to effect operation of said clutch mechanism to thereby initiate and determine said feed and traverse carriage movements, disposed to vary the feed of said turret carriage during movement thereof, disposed to select the spindle speed in said headstock and disposed to control the movement of said slide in correlation to the indexed position of the turret.

24. In an automatic turret lathe, a bed, a headstock having a rotary spindle, means in said headstock to drive said spindle at a selected speed, a turret carriage on said bed, a turret mounted on said carriage and adapted to be successively indexed to selected positions, a tool carriage, a tool slide for said carriage, means disposed to drive said turret carriage and to feed the same at a rate correlated to the selected spindle speed, means disposed to drive said tool slide, a master control drum on said bed, means disposed to index said drum in correlation to the indexing of said turret, and separate inter-engaging means on said control drum and said turret carriage disposed to select the spindle speed and disposed to regulate the feed of said turret carriage and slide in correlation to the indexed position of said turret.

25. In an automatic lathe, a bed, a turret carriage on said bed, a turret on said carriage and indexable successively to selected operative positions, a tool carriage on said bed, a tool slide for said tool carriage, means disposed to drive said turret carriage, means disposed to drive said tool slide, means disposed to move said tool carriage on said bed, and separate means on said bed correlated with the indexed position of said turret and disposed to engage and actuate control mechanism on said turret carriage during movement of the carriage to effect a control of the movement of said tool carriage, the feeding of said tool slide, and the initiating and determining of the feed of said turret carriage.

26. In an automatic lathe, a bed, a headstock having a rotary spindle, means in said headstock for driving said spindle at a speed selected from a group of predetermined speeds, a turret carriage on the bed, a turret on said carriage and indexable successively to selected operative positions, a tool carriage intermediate said headstock and turret carriage, a slide for said tool carriage having a tool post mounted thereon, means disposed to drive said turret carriage in traverse, means alternative to said last named means disposed to feed said turret carriage at a rate correlated to the spindle speed, means disposed to drive said slide, and a master control drum indexable with said turret and disposed adjacent the path of movement of said turret carriage with separate means thereon adapted to engage corresponding control members on said carriage to selectively initiate and determine the traverse

and feed of said turret carriage, select the spindle speed and initiate and regulate the feed of said slide in correlation to the indexed position of said turret.

27. In an automatic lathe, a bed, a headstock having a rotary spindle, means in said headstock for driving said spindle at a speed selected from a group of predetermined speeds, a turret carriage on the bed, a turret on said carriage and indexable successively to selected operative positions, a tool carriage intermediate said headstock and turret carriage, a slide for said tool carriage having a tool post mounted thereon, means disposed to drive said turret carriage in traverse, means alternative to said last named means disposed to feed said turret carriage at a rate correlated to the spindle speed, means disposed to move said tool carriage to a predetermined selective operating position, means disposed to drive said slide, and master control means disposed adjacent the path of movement of said turret carriage with separate members thereof adapted to engage corresponding control members on said carriage to selectively initiate and determine the traverse and feed of said turret carriage, initiate the movement of said tool carriage, select the spindle speed and initiate and regulate the feed of said slide in correlation to the indexed position of said turret.

28. An automatic turret lathe comprising a bed, a reciprocating carriage on said bed adapted to have traverse movement in both directions of reciprocation and feed movement in at least one direction of reciprocation, a turret mounted on said carriage and adapted to be successively indexed to predetermined selected positions, means disposed to automatically index said turret to a successive operating position upon completion of an operation for one indexed position thereof, a master control drum on said bed and indexed in correlation to the indexing of the turret, means disposed to feed said carriage, separate means disposed to traverse the carriage, clutch mechanism on said carriage disposed to connect the feed and traverse drives selectively, inter-engaging means on said drum and carriage disposed to effect operation of said clutch mechanism and to initiate and determine said feed and traverse carriage movements in correlation to the indexed position of the turret, and additional inter-engaging means on said drum and carriage disposed to regulate the feed of said carriage in correlation to the carriage movement.

29. In an automatic turret lathe having a bed, a carriage and a turret mounted on said carriage, a master control drum mounted on said bed and extending longitudinally in the direction of movement of the carriage, said control drum having a plurality of index faces corresponding to the index faces of said turret, each of the operative index faces of the control drum having thereon a trip adapted to engage a control member on said carriage upon forward rotation of the drum for initiating the forward traverse of the carriage and a cam member adapted to engage a control member on said carriage upon forward traverse of the carriage for selectively disconnecting said traverse and initiating the forward feed of said carriage, a stop disposed to determine the forward feed and initiate the back traverse of said carriage, means responsive to the back traverse of said carriage and disposed to automatically initiate indexing of said turret and control drum to a successive operating position, a cam member on each operative face of the drum

engaged by a follower on said carriage as the latter moves forwardly to control the feed of the carriage, a tool post slide for the lathe, means disposed to feed said slide and to back traverse the same, and a cam member on each operative face of the drum engaged by a follower on said carriage to control the feed and back traverse of said slide in correlation to the movement of said carriage and the indexed position of said drum.

30. In an automatic turret lathe having a bed having a headstock at one end, a carriage adapted to move on said bed toward and away from the headstock, a turret mounted on the carriage, a master control drum mounted on said bed and extending longitudinally adjacent the path of movement of said carriage, a drive shaft extending longitudinally of the bed to drive the carriage from the headstock, a clutch disposed to connect and disconnect said shaft from the carriage drive, interconnected mechanism adapted to be driven by said shaft to index and turret and drum in correlation to each other, a clutch disposed between said drive shaft and indexing mechanism to index said turret and control drum, trip mechanism operable by the back traverse of the turret carriage to engage said last named clutch and effect indexing operations, and trip mechanism operable to disengage said clutch when said turret and control drum have rotated to the next operative index position.

31. In an automatic turret lathe having a bed, a carriage and a turret mounted on the carriage, a master control drum mounted on said bed and extending longitudinally adjacent the path of movement of said carriage, means disposed to index said turret and control drum simultaneously and in correlation, a lost motion drive connection for the indexing of said drum, means disposed to effect a sudden forward rotary movement of the drum at the end of each indexing operation and to secure the drum in indexed position, and a trip operable by said sudden forward movement of the drum and disposed to initiate the next cycle of operation of the lathe corresponding to the indexing of the turret.

32. In a lathe or the like, a headstock having a rotary work carrying spindle, means disposed in said headstock to drive said spindle at any one of a plurality of selected speeds, a tool carrying member requiring feeding movement at a variable speed within a wide range of speeds, a motor pump unit disposed to drive said member, means correlated with said spindle drive and disposed to drive the shaft of said pump at a speed determined by said selected spindle speed, and means correlated with the movement of said tool carrying member and disposed to vary the displacement of said pump and thereby regulate the feed for said member.

33. In an automatic lathe or the like, a stationary bed, a carriage adapted to move on said bed, a hydraulic motor-pump unit carried by said carriage and adapted to drive the same on said bed at a selected rate determined by the volume of liquid supplied to the motor by the pump, means on said bed disposed to supply said pump with initially low pressure liquid, and telescopic conduit means interposed between said movable carriage and bed and disposed to transmit said low pressure fluid to said pump from said first named means.

LOUIS E. GODFRIAUX.
